UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A STABLE.

SPECIFICATION forming part of Design No. 19,369, dated October 22, 1889.

Application filed September 28, 1889. Serial No. 325,452. Term of patent 3½ years.

To all whom it may concern:

Be it known that I, ANTOINE LACROIX, Jr., of the city of Brooklyn, in the county of Kings and State of New York, have invented 5 and produced a new and original Design for the Exterior of a Stable, of which the following is a specification, reference being had to the accompanying drawings, forming a part thereof.

10 Figure 1 represents a front elevation; Fig. 2, a side elevation of a stable of my design, and Fig. 3 a horizontal section or plan of the lower story thereof.

15 Similar letters of reference designate corresponding parts thereof.

A stable of this design consists of two stories, the lower story having the front and side walls and the lower portion of the rear wall upright, and the upper story being within 20 a gable roof, the eaves of which at the rear project beyond the rear wall in the form of a shelter with bracket supports, as I will now proceed to more particularly describe in detail with reference to the drawings.

25 The plan of this design is in the form of a parallelogram. The main roof A is gabled, the ridge a of the gable running in a direction from side to side, the eaves in front being

nearly at the level of the floor of the second story, but the slope of the roof being prolonged 30 at the rear to bring the eaves lower there than the eaves in front and cause them to project beyond the rear wall, as shown at b in Fig. 2. The portion of the roof so projecting at b has cantilevers c between it and the rear wall, as shown in Fig. 2. The gable ends of the main roof are sloped from the ridge downward, as shown at d d in Fig. 1.

Centrally to the front of the design there projects from the main roof A a gable B, the 40 lower part e of the end of which is nearly flush with the front wall, and the upper part f of which projects forward over the door of the upper story, as shown in Figs. 1 and 2. Parts of the eaves of the front of the main 45 roof project, as shown at g, in front of the gable B; but below these parts g the gable end is flush with the front wall.

What I claim is—

The design for the exterior of a stable, substantially as herein shown and described.

ANTOINE LACROIX, JR.
